UNITED STATES PATENT OFFICE.

OTTO C. F. WILCKE AND JOHN KIRBY, JR., OF DAYTON, OHIO, ASSIGNEES TO THE DAYTON MANUFACTURING COMPANY, OF DAYTON, OHIO, A CORPORATION OF OHIO.

SHADE HOLDER.

Application filed October 16, 1922. Serial No. 594,847.

To all whom it may concern:

Be it known that we, OTTO C. F. WILCKE and JOHN KIRBY, Jr., citizens of the United States, residing in the city of Dayton, in the 5 county of Montgomery and State of Ohio, have invented certain new and useful Improvements in Shade Holders; and we do hereby declare the following to be a full, clear, and exact description of same, reference being had to the accompanying drawings, and to the reference numerals marked thereon, which form a part of this specification.

Our invention while being particularly 15 applicable to lighting fixtures for use in railway cars is also applicable to lighting fixtures for other uses: and one of its objects is to combine with such fixtures a holder for the shades or globes used in connection 20 therewith which will be efficient, durable, of simple construction and of low cost to manufacture, and which will support the shade or globe rigidly in place and be sufficiently elastic or yielding to prevent 25 rattling or breaking under the jars and vibrations incident to moving cars or other vehicles: and it contemplates the performance of such function without other assisting means of support for the shade or globe. 30 Another object of the invention is to provide a shade-retainer that will permit of the shade being forced into position therein or withdrawn therefrom, without danger of dislodgement of the retainer, when the latter is free from restraint and freely movable 35 in its supporting channel, and which when thus inserted will hold the shade from falling of its own weight, so that without adjustment of the operative parts of the fixture a number of shades may be inserted before the process of final adjustment takes 40 place, another object being to provide means for preventing undue separation of the operative parts of the fixture.

The invention consists in certain new and novel combination of elements, which will be hereinafter fully described and claimed.

In the said drawings Figure 1 represents a side view of the fixture having a shade held therein, and showing one half in full and one half in section.

Fig. 2 is a broken perspective view of the body ring, showing provision for a modified form of attachment to a supporting medium.

Fig. 3 is a broken detached perspective

view of the outer ring or casing, shown partly in section.

Fig. 4 is a broken, detached, perspective view of the ring which forms the upper wall of the channel or groove in which the shade 60 retaining ring is carried.

Fig. 5 is a similar view of the shade-retaining ring, and Fig. 6 is an inverted plan view of the same.

Similar reference numerals indicate corresponding parts in all the figures of the drawings, in Fig. 1 of which drawings the supporting ring of the fixture is shown attached to a base plate 1 by which it may be secured to the deck-rail of a car or to any 70 suitable supporting surface, while in Fig. 2 the said ring is shown attached to a contracted upwardly extension 2 which may be provided with means for attachment to a bracket or other support, but as the invention relates 75 only to the means for holding the shade or globe in position the method of its attachment to any particular support is immaterial and may be varied to suit requirements. In the embodiment of our invention we have 80 contemplated reducing to a minimum, consistent with efficiency and durability, weight, and cost of production and to that end we have illustrated the same in a manner which presents itself as most conducive to that 85 accomplishment, it is obvious, however, that various modifications may be made in the structural details without departing from the spirit of our invention, therefore, we do not wish to be limited to the exact construction shown in the drawings or described in this specification.

Further referring to the drawings and the reference numerals marked thereon, 3 represents the supporting ring of the fixture and it 95 comprises an exteriorly screw threaded annulus rounded at its lower edge, at 4, and having a reduced extension 5 to which may be attached either of the forms 1 or 2 (shown in Figs. 1 and 2) or to any other support 100 adapted to the thing to which the fixture is to be attached. 6 represents an internally screw threaded ring adapted to engage the threads of the ring 3 and to operate thereon; this ring, 6, is incased in and carried by an outer ring or casing, preferably formed of sheet metal, to which it is secured and which 105 comprises a vertical ring or band 7 whose lower end terminates in an inwardly disposed horizontal flange 8 and whose upper 110

end is provided with a suitable number of extension clips 9, the band being also provided with a knurled swaged or beaded portion 10, and a depression 11 forming a seat 5 for the ring 6. At the bottom of and secured within the casing, above the flange 8, there is located a ring or collar 12 having a downwardly extending flange 13, and which in conjunction with the flange 8 10 forms a circumferential groove or channel 14 the width of which is determined by the depth of the flange 13, the bottom edge of which rests on the flange 8, as clearly shown in Figure 1.

15 The shade retainer is represented by the numeral 15 and it comprises a sheet metal spring acting ring of substantially the form shown in the drawings, a section of which is cut away at 16 for a purpose to be hereinafter explained, in its formation this ring embodies a horizontally disposed portion 17 adapted to be loosely mounted in the channel 14 and, within certain limits, to move freely therein. Continuing from the said 20 horizontal portion the ring, in cross-section, follows substantially the contour of the neck 18 of a shade 19 and then partakes of a downwardly and outwardly disposed incline portion 20 which terminates, just above the 25 outer edge of the member 17, in a horizontally disposed narrow portion 21 whose function is to contribute stiffness to the incline portion 20.

30 In assembling the device the shade-retainer 15 is first inserted in position in the channel 14, as clearly shown in Figure 1, which is done by contracting the same and springing it into place, the open space 16 being provided to allow for such contraction 35 in addition to providing for contraction and expansion of the retainer in performing its function in holding and releasing the shade.

40 The screw-threads of rings 3 and 6 are then brought into operative engagement, 45 and with the device thus assembled the extension clips 9 are bent inward to project beyond the inside of the ring 6, their function being to limit downward movement of the ring 6 by contacting with a shoulder 22 50 formed on the ring 3 and thus to prevent undue separation of the said rings.

55 The operation of the device is as follows: When a shade is to be inserted the knurled swage 10 is gripped by the operator and the casing turned in a direction to move the ring 6 downward carrying with it the shade-retainer 15, this frees the latter from contact 60 with the body-ring 3 and leaves it free to expand to permit the end of the shade to be forced through the opening of the retainer which will then contract and engage the neck 18 of the shade, as shown in Figure 1,

and as the inside diameter of the retainer is substantially the same as the outer diameter of the neck of the shade the latter will be held from falling of its own weight until it is more firmly secured by reversing the movement of ring 6, thereby bringing the incline portion 20 into hard engagement with the end 4 of ring 3, which centers and further contracts the retainer to hold the shade firmly in position.

We claim as our invention:

1. In a shade holder, in combination, an externally screw threaded body ring adapted to be attached to a fixed support, a casing ring surrounding the same and being in threaded engagement therewith, a circumferential channel formed in said casing ring at the bottom thereof, and a resilient shade retainer comprising a single non-continuous sheet metal ring loosely mounted in said channel; said retainer having a portion which in cross section conforms substantially to the neck of the shade and an incline portion extending downwardly and outwardly therefrom adapted to engage the supporting ring upon upward movement of the casing ring and thereby to circumferentially compress the retainer causing it to grip the shade and hold it firmly therein.

2. In a shade holder, an externally screw threaded body ring adapted to be attached to a fixed support, a casing ring surrounding the same and being in threaded engagement therewith, a circumferential channel formed in said casing ring at the bottom thereof, a resilient shade retainer comprising a single non-continuous sheet metal ring loosely mounted in said channel and whose normal inside diameter is substantially the same as the outer diameter of the neck of the shade which it is designed to support; the same being capable of sufficient spring action to permit of passage of the end of the shade and to return to its normal diameter when obstruction thereto is removed, said retainer having a shade engaging portion which in cross section conforms substantially to the neck of the shade; and an incline portion extending downwardly and outwardly therefrom, in combination with means for engaging said incline portion to circumferentially contract the retainer and cause the same to grip the shade and hold it firmly therein.

In testimony whereof we hereunto affix our signatures in the presence of two subscribing witnesses.

OTTO C. F. WILCKE.
JOHN KIRBY, JR.
